PAIR OF FOOD TONGS OR SIMILAR ARTICLE

Nathan W. Roop, Columbus, Ohio, assignor to
Columbus Plastic Products, Inc., Columbus,
Ohio, a corporation of Ohio

Application October 1, 1951, Serial No. 16,796

Term of patent 14 years

(Cl. D44—4)

To all whom it may concern:

Be it known that I, Nathan W. Roop, a citizen of the United States, residing at Columbus, in the county of Franklin and State of Ohio, have invented a new, original, and ornamental Design for a Pair of Food Tongs or Similar Article, of which the following is a specification, reference being had to the accompanying drawing, forming a part thereof.

Fig. 1 is a perspective view of a pair of food tongs or similar article, showing my new design;

Fig. 2 is a plan view of the tongs when in assembled order;

Fig. 3 is a side elevational view of the tongs looking toward the forked side thereof;

Fig. 4 is a similar view disclosing the opposite or spoon side of the tongs.

I claim:

The ornamental design for a pair of food tongs or similar article, substantially as shown.
NATHAN W. ROOP.
